UNITED STATES PATENT OFFICE.

WILEY W. RAINWATER, OF CREWS, TEXAS.

TELEPHONE ATTACHMENT.

1,198,765.

Specification of Letters Patent. Patented Sept. 19, 1916.

Application filed October 29, 1914. Serial No. 869,269.

To all whom it may concern:

Be it known that I, WILEY W. RAINWATER, a citizen of the United States, residing at Crews, in the county of Runnels and State of Texas, have invented certain new and useful Improvements in Telephone Attachments; and I do hereby declare the following to be a full, clear, and exact description of the invention, such as will enable others skilled in the art to which it appertains to make and use the same.

This invention relates to new and useful improvements in telephone attachments and has for its principal object to provide a device which is designed to eliminate waste of current from the batteries used in connection with the telephone.

Another object of the invention is to provide a means for cutting out the battery circuit entirely and connecting the line so as to prevent interference with other telephones.

Still another object of the invention is to provide a switch for locating a dead box in the line which will eliminate much time and trouble which is usually necessitated in the ordinary systems when a switch of this character is not used.

A further object of this invention is to provide a switch of the above class which eliminates the necessity of holding the switch in contact without inconveniencing the user.

A still further object of the invention is to provide a device which will leave the transmitter circuit inoperative and still enable the listening circuit to be cut in, thus permitting the listener on the line to hear without interfering with the parties talking and relieves any stress on the batteries of the telephone.

With these and other objects in view, the invention consists in the novel combination and arrangement of parts which will be fully set forth in the following specification and accompanying drawing, in which,

Figure 1 is a side view of the telephone showing this attachment as it would appear when attached thereto, Fig. 2 is a transverse sectional view taken on line 2—2 of Fig. 1, and Fig. 3 is a transverse sectional view taken on line 3—3 of Fig. 1.

Referring now to the drawing by characters of reference, the numeral 1 designates as an entirety the casing of the telephone

which is provided with the usual bells 2, 55 transmitter 3 and magneto crank 4. Secured to one side of the casing 1 is the plate 5, which plate is notched as at 6 to receive the sliding button which will be more fully hereinafter described. A similar pair of 60 plates 7 and 8 respectively are secured to the side of the casing 1 and these plates are provided with the reduced extensions 9 and 10 respectively which are of the same width as the width of the portions between 65 the notch 6 and the lateral edges of the plate 5. These plates are spaced from each other as clearly shown in Fig. 1 and the undersides of the inner edges on the portions 9 and 10 and the portions between the 70 slot 6 and the lateral edges of the plate 5 are cut away as at 11 to form guides for the button designated generally by the numeral 12. This button 12 comprises the handle portion 13 which may be of any suitable 75 material and this handle portion has projecting from the base thereof the tubular extension 14 which terminates at its inner end in the flange 15, which flange is arranged to lie in the cutaway portion 11 and prevent 80 the button from being displaced. Projecting inwardly from each of the plates 7 and 8 are the extensions 16 carrying at their outer ends the binding post 17 to which the wires 18 are secured.

It will be apparent from the foregoing that in use, the plates 7 and 8 are secured to the telephone in any suitable manner so that the tubular members 16 project 90 through the casing thereof and are connected respectively in circuit with the battery circuit so that the plates will form a break therein unless the button 12 is pushed so as to form a contact therebetween. It will thus be seen that a considerable saving 95 in the battery is effected due to the fact that should a person lift the receiver from the hook when they listen over the line, unless the button 12 is pushed into the proper position, any transmission from that particular 100 form is cut out. In view of this fact it will be clearly seen that considerable saving will be effected and any leak or waste of current from the battery prevented.

While in the foregoing there has been 105 shown and described the preferred embodiment of this invention, it is to be understood that such changes may be made in the

combination and arrangement of parts as will fall within the spirit and scope of the appended claim.

What is claimed is:—

- 5 In an electric switch including a casing, a pair of spaced plates secured thereto having their inner opposed edges cut away for a groove, a button slideable between the plates and located in the groove bridging the space between the said plates, and a battery circuit, said plates being in said circuit, said button contacting with said plates completing the circuit through the battery,
- 10

and a retaining plate at one end of the first named plates and provided with a slot 15 aligned with the groove formed by the first named plates, said slot of the last named plate being arranged to receive the button therein holding the same out of contact position.

20

In testimony whereof I affix my signature in presence of two witnesses.

WILEY W. RAINWATER.
